US0D1078812S

(12) **United States Design Patent** (10) Patent No.: **US D1,078,812 S**
(45) Date of Patent: ** Jun. 10, 2025

(54) **ROBOT**

(71) Applicant: **NVIDIA Corporation**, Santa Clara, CA (US)

(72) Inventors: **Claire Delaunay**, Menlo Park, CA (US); **Kenneth William MacLean**, Santa Clara, CA (US); **Gabriele Pasqualino**, Sunnyvale, CA (US); **David Weikersdorfer**, Mountain View, CA (US); **Gregor Markus Kopka**, Bothell, WA (US)

(73) Assignee: **NVIDIA Corporation**, Santa Clara, CA (US)

(**) Term: **15 Years**

(21) Appl. No.: **29/844,509**

(22) Filed: **Jun. 29, 2022**

(57) **CLAIM**

The ornamental design for a robot as shown and described.

DESCRIPTION

FIG. 1 depicts a perspective view of a robot showing our new design.

FIG. 2 depicts a front view thereof.

FIG. 3 depicts a back view thereof.

FIG. 4 depicts a left side view thereof.

FIG. 5 depicts a right side view thereof; and,

FIG. 6 depicts a top view thereof.

The dash lines represent portions of the article forming no part of the claimed design.

1 Claim, 6 Drawing Sheets

FIG. 1

FIG. 2

FIG. 3

FIG. 4

FIG. 5

FIG. 6
